UNITED STATES PATENT OFFICE

2,470,399

EJECTOR TYPE SOCKET WRENCH

Frank Holben, Middletown, R. I.

Application March 8, 1945, Serial No. 581,584

1 Claim. (Cl. 81—124.1)

1

This invention relates to an ejector-type socket wrench, that is, a special type of wrench embodying a shank having a hand-grip at one end and a socket at the other end, means being associated with and incorporated in the grip and shank to eject nuts or bolts from the socket.

More specifically, one embodiment of the invention relies for novelty on a spring-return plunger mounted for reciprocation in the handle and shank assembly, the plunger rod having a hand-knob located in a projecting position beyond one end of the hand-grip to permit the latter to be employed with convenience and expediency for loosening or tightening nuts and bolts, after which the knob on the plunger may be expediently employed to dislodge and eject the nut from the socket.

Another phase of the invention has to do with a slightly different form of plunger arrangement in which the plunger rod is operated by a simple finger-piece projecting through a side slot in the shank.

Other features and advantages will become more readily apparent from the following description and the accompanying illustrative drawings.

In the drawings, wherein like numerals are employed to designate like parts throughout the views:

Figure 1 is a side elevational view of a hand-grip type socket wrench embodying ejector means constructed in accordance with the principles of the present invention.

Figure 2 is a longitudinal central sectional view on the plane of the line 2—2 of Figure 1.

Figure 3 is a cross section on the line 3—3 of Figure 2.

Figure 4 is a cross section through the shank on the line 4—4 of Figure 2.

Figure 5 is a view like Figure 2, that is, a longitudinal section and elevational view showing a modified form of the invention.

Figure 6 is a perspective view of the plunger unit employed in the arrangement depicted in Figure 5.

Figure 7 is a fragmentary elevational view of an end portion of the tubular shank.

Figure 8 is an enlarged fragmentary detail sectional and elevational view of the operating member on the reciprocating plunger rod.

Reference is had first to Figures 1 to 4, inclusive. Here, the tubular shank 9 is provided in one end with a polygonal socket 10. The inner or upper end of said shank projects into a socket 11 in the wooden or equivalent hand-grip 12. The

2

hand-grip is centrally bored and the bore extends through opposite ends and is enlarged at one end to form the socket 11. There is an intermediate and smaller socket at the point 13 and a still smaller reduction at the point 14. The tapered end of the hand-grip is provided with a ferrule 15 held in place by retention and assembling pins 15a which also serve to anchor the shank in the socket 11. The reciprocating plunger rod 16 extends completely through the bore in the hand-grip and also through the central bore or passage in the shank 9. This rod is provided at one end with an ejector head 17 and at its opposite end with a smaller head 18 which constitutes a hand-knob or thrust member. A coiled spring 19 is located in the socket 13 and surrounds the plunger-rod and bears at one end against the stop collar 20 on said plunger-rod and is also confined in said socket 13. The opposite end of the spring rests upon the adjacent end of the shank 9, thus utilizing this end of the shank as a shoulder for said spring.

In practice, the spring 19 bearing against the parts 9 and 20 serves to retain the ejector disk or head 17 in the socket 10 in a receding position. The spring also serves to place the operating knob 18 in a projected position in readiness for use. It is evident that by pressing the knob 18 against the tension of the spring, the ejector disk 17 forces a nut (not shown) out of the socket 10.

Referring now to the modification seen in Figures 5 to 8, inclusive, certain parts correspond to those already described and shown in Figures 1 to 4. That is to say, the cylindrical wooden hand-grip 12a in this instance is merely provided with a socket which comprises an inner enlarged portion 11a and a reduced coaxial axial socket 13a. The inner end of the tubular shank 9a extends into the socket 11a and is fastened in place by the parts 15 and 15a already described. The plunger-rod 16a is provided with an ejector disk or head 17a normally confined in the socket 10a. The rod 16a terminates within the limits of the socket 13a and is provided with a stop collar 20a with which the coil spring 19a engages. The spring surrounds the rod and rests upon the adjacent inner end of the shank 9a. In this arrangement the shank is provided at one side with an elongated slot 21 to accommodate the operating member 22. This member comprises a ball on the outer end of a stem which stem is threaded into the operating rod as shown 55 to advantage in Figure 8. Thus, we have a choice

of two different ways of projecting the ejector rods 16 or 16a.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

In a tool of the class described, an elongated hand-grip, said hand-grip being centrally and axially bored and the bore extending through opposite ends of the hand-grip, said bore embodying graduated portions of varying diameters defining, at one end, a shank accommodating 15 socket, a spring accommodating socket intermediate the hand grip ends, and a restricted plunger rod guide, the latter being at the inner or free end of the hand-grip, an elongated tubular shank having its inner end telescoping and 20 secured in the shank accommodating socket of the hand-grip, said shank being provided at its

5 outer or working end with a socket wrench, a plunger rod extending through the bore of the shank and having a head on its outer end located in said socket wrench, said rod also extending through and beyond remaining portions of the bore in said hand-grip and terminating at its other end in an operating knob, said knob being arranged exteriorly of the adjacent end of the hand-grip, a shoulder on said rod located in the 10 spring accommodating socket, and a coiled spring confined in said socket surrounding said rod and bearing against said shoulder and also against the adjacent inner end of said shank.

FRANK HOLBEN.
